UNITED STATES PATENT OFFICE

HUGH A. MCGILL, OF DETROIT, MICHIGAN

AUTOMATIC FEEDING MACHINE

Application filed January 18, 1926. Serial No. 82,054.

My invention relates to a new and useful improvement in an automatic feeding machine adapted for feeding work pieces individually to a machine in which the work 5 piece is held by a pair of cooperating parts while the work is being performed. The device may be used on various types of machines such as screw machines, milling machines, grinding machines, etc. and in the drawings 10 I have shown the invention applied to a grinding machine of a well known type.

It is the object of the present invention to provide a mechanism whereby work pieces may be automatically fed individually to the 15 machine and automatically secured in the machine preliminarily to the work performing operation and again automatically released and replaced by a succeeding work piece upon the completion of the working 20 operation.

Another object of the invention is the provision of an automatic feeding mechanism of this class which will be simple in structure, economical of manufacture, highly efficient 25 in use and adaptable for use on various types and kinds of machines.

Another object of the invention is the provision in an automatic feeding mechanism of this class of magnetically operated means 30 for carrying and placing the work piece in operation and of automatic means for de-energizing the magnetic means so that the work piece will be released by the feed mechanism when carried to the proper position.

35 Other objects will appear hereinafter.

The invention consists in the combination and arrangement of parts hereinafter described and claimed.

40 The invention will be best understood from a reference to the accompanying drawings, which form a part of this specification and in which;

Fig. 1 is a top plan view of the machine embodying the invention.

Fig. 2 is a vertical cross sectional view with parts broken away taken on substantially line 2—2 of Fig. 1.

50 Fig. 3 is a fragmentary sectional view taken on substantially line 3—3 of Fig. 2

showing parts in elevation and parts in section.

Fig. 4 is a front elevational view of the machine shown in Fig. 1 with parts broken away.

Fig. 5 is a sectional view taken on substantially line 5—5 of Fig. 4 slightly enlarged.

Fig. 6 is a sectional view taken on substantially line 6—6 of Fig. 1.

Fig. 7 is a sectional view taken on substantially line 7—7 of Fig. 2.

Fig. 8 is a front elevational view of the face plate used in the invention taken on substantially line 8—8 of Fig. 1.

Fig. 9 is a fragmentary sectional view taken on substantially line 9—9 of Fig. 8 showing parts in elevation and parts in section.

Fig. 10 is a sectional view taken on substantially line 10—10 of Fig. 12.

Fig. 11 is a fragmentary sectional view taken on substantially line 11—11 of Fig. 10.

Fig. 12 is a sectional view taken on substantially line 12—12 of Fig. 10.

Fig. 13 is a diagrammatic view of the wiring used in the invention.

The invention as shown in the drawings is illustrated as applied to a power traverse grinding machine of a well known type with a belt drive. The structure and detail of this machine are well known to those skilled in the art and the parts of the machine are referred to only where it is deemed necessary to clearly explain the position and method of mounting the present invention.

The machine with which the invention is 85 illustrated comprises a supporting bed 22 slidably mounted upon which is a carriage 23. The machine is provided with a shaft 24 which is rotated by the gear wheel 25 in the usual manner—the shaft 24 serving to effect 90 a reciprocation of the carriage 23 on the bed 22. As previously stated the machine illustrated is a power traverse machine.

The grinding wheel 26 is covered by a shield 27 and rotated by means of the belt 28. 95 The machine is provided with the usual cone 29 adapted for driving the face plate 30—the face plate cooperating with a tail stock 31 to retain and hold the work piece 31 in position during the grinding operation.

Projecting upwardly from the bed 22 are standards 32 and 33 which are positioned at opposite sides of the bed 22 each serving to form at its upper end a bearing for shafts 34 and 35, respectively—upon each of which is mounted a sprocket wheel 36 exterior of the support 32 or 33 as the case may be. Positioned over these sprocket wheels 36 are sprocket chains 37 which also pass around sprocket wheels mounted upon the shaft 38—the shaft 38 being driven by suitable power means 39 which are connected by the chain 40 to a sprocket wheel fixedly mounted upon the shaft 38. The sprocket wheels 36 are fixedly mounted upon the shafts 34 and 35. Fixedly mounted upon the shafts 34 and 35 are sprocket wheels 41 which cooperate with sprocket chains 42 and 43 which pass around guide plates 44 and 45—said guide plates extending downwardly in inclined position and terminating at their upper ends at the outlet portion 46 of a hopper 47 in which the work pieces are passed. The outlet 46 is provided with a suitable conveyor driven by the chain 48 so that the work pieces are delivered singularly to the outlet end of the outlet 46. The chain 48 being suitably timed with the rest of the mechanism. Each of the plates 45 and 44 is provided at its outer side with a boss 50 in which is formed a pocket for the reception of the inner end of the shafts 34 and 35.

Positioned between the plates 44 and 45 is an electro-magnet 51—projecting outwardly from each side of which are studs 52 and 52'. Each of these studs engages in a slot 53 formed in the plates 44 and 45. The slot 53 in plate 45 is provided with a contact member 53' extending the full length of the slots so that the electro magnet 51 may be energized at will, as shown in Fig. 3. Projecting outwardly from each side of the electro-magnet 51 adjacent the upper end thereof are shafts 54 and 55 which engage in the elongated longitudinally extending slots 56 formed in the plates 44 and 45. Extending upwardly from the shafts 54 and 55 are L-shaped brackets 57 and 58 which are connected to the sprocket chains 42 and 43 respectively so that as the chains 42 and 43 travel around their sprocket wheels they carry the electro-magnet longitudinally of the plates 44 and 45. As the chain carries the electro-magnet 51 toward the upper end of the plates 44 and 45 the cores 51' are energized and serve to lift the work piece which is formed of metal from the discharge end of the outlet 46. As the chains 42 and 43 continue their travel the electro-magnet moves downwardly into the position shown in full lines in Fig. 1, Fig. 2, Fig. 3 and Fig. 4 at the lower end thereof—at which time the electro-magnet has carried the work piece into alignment with the center of the face plate and the tail stock. At this time the electro-magnet de-energizes. Simulta-

neously with the de-energizing or just previously to the de-energizing of the electro-magnet 51 the magnetic coil 59 is energized about the core 60 so as to attract the disc 61 which is mounted upon the shaft 62 which carries an additional disc 63 and is provided at its end with the tail stock 31. These discs are mounted in the housing 64 which is shown clearly in Fig. 3. The tail stock striking the work pieces forces it against the head of the face plate which is clearly shown in Fig. 8 and Fig. 9. The face plate 30 having a cup-shaped flange 65 projecting outwardly from one face thereof concentrically thereof. Swingably mounted in the cup-shaped member 65 is a horse shoe shaped gripping member 66 which is normally held in the position shown in full lines in Fig. 9 by means of the spring 67. As soon as the work piece 31', which in the present instant may be considered to be a bolt is forced into the cup-shaped member 65 the arm 68 will be engaged by the end of the head of the bolt. This will force the U-shaped engaging member 66 to rock on its mountings as a pivot so as to bring the end 69 into engagement with the sides of the bolt head to firmly grip the bolt head and effect its rotation in unison with the face plate 30.

The electric control is operated by the control drum 70 which is mounted upon the shaft 71 which is journaled in the housing 72 shown in Fig. 1, Fig. 2 and Fig. 4. The shaft 38 projects through the housing 72 and carries a fixedly mounted sprocket wheel connected by the chain 73 to a sprocket wheel fixedly mounted upon the shaft 71 upon which the drum 70 is fixedly mounted. On the periphery of the drum 70 is a metallic band 74 which engages the contact 75, which is electrically connected to a suitable source of electrical energy the band 74 being connected to the electro-magnet 51 so that when the band 74 engages the brush or contact 75 the electro-magnet 51 is energized.

Mounted on the periphery of the drum 70 is an interrupted metallic band 76 which engages the contact 77—the contact 77 being suitably connected to a source of electrical energy and the band 76 being suitably connected to one end of the coils 59 so as to energize the cores 60 when the circuit is closed through contact with the band 76 and the brush or contact 77.

As soon as the work piece 31' is engaged between the face plate and the tail stock as described the carriage 23 is moved automatically to bring the work piece into engagement with the grinding wheel 26. This automatic movement is effected by a closing of the circuit to the motor 78 by means of the engagement of the metallic band 79 with the brush 80 which is suitably connected to a source of electrical energy 80'—the motor effecting a rotation of the gear wheel 25

through a reduction gearing 81. This gear 81 is fixed to the motor shaft 81' to transmit the power to the lead screw 105 through the reduction gear 106 fixed on the shaft 24, and thence to the gear wheel 25, and to the gear wheel 107 which is fixed to the lead screw 105 which in turn is engaged by a depending thread portion 23', substantially effecting reciprocation of the carriage 23 for the purpose heretofore mentioned. This feature of the machine is of a well known structure and consequently not illustrated in detail.

As the carriage 23 begins its movement the rod 82 which is mounted in a depending portion 83 of the carriage 23 approaches a stop 84. The rod 82 is provided with a movable tongue 85 which engages the ratchet wheel 86 also mounted in the depending portion 83. As the carriage moves the rod 82 is forced backward against the pressure of the spring 87 mounted upon the rod 82 and serves to throw the ratchet wheel around one notch, thus causing a reversing of the field current of the motor 78 which drives the gear wheel 25. This is accomplished through the contact disc 88 which cooperates with the ratchet wheel 86. Mounted upon the disc 88 are the contact points 89. Positioned in the depending portion 83 so as to alternatively engage the contact points 89 are the spring pressed contact lugs 90. These contact points 90 are so positioned so as to alternately make contact with the points 89 thus reversing the field current of the motor. A rod 91 whose action is similar to the action of the rod 82 is used to throw the ratchet when the carriage is moving in the opposite direction and is used in conjunction with a stop 92 similar to the stop 84. As the carriage in its movement brings the work piece closer to the grinding wheel the speed of the motor driving the gear wheel 25 is automatically slowed through means of a resistance mounted in the line.

The current driving the motor is delivered from the circuit 2 through the wire 93 to a bus bar 94. This bus bar receives the full current and the motor is then run at normal speed. The current is transferred to the motor from the bus bar through means of the brush 95 mounted upon the depending portion of the carriage 83—said brush in turn delivering the current to the contact disc 88. As the carriage moves the work piece toward the grinding wheel the brush passes from the bus bar 94 to the bus bar 96 which is insulated from the bus bar 94 and carries a lower current than the bus bar 94. This is accomplished by means of a rheostat or other variable resistance 97 mounted in the line and connected to the bus bar 96. This serves to slow down the speed of the carriage as the work is brought to the grinding wheel so that the work is not fed into the wheel too rapidly, thus preventing the undue wearing or

possible breakage of the grinding wheel. As the carriage travels sufficiently to bring the work piece to the desired position for completing the operation, the band 103 on the drum 70 engages the contact 104, which is connected to a suitable source of electrical energy thus energizing the coil 59' which is positioned about the core 60' at the same time that the coil 59 is de-energized, thus effecting retraction of the shaft 62 so as to release the work piece, the operator removing the work piece manually.

While I have illustrated and described the preferred form of structure, I do not wish to limit myself to the precise form of structure shown, but desire to avail myself of such variations and modifications as come within the scope of the appended claims.

Having thus described my invention what I claim as new and desire to secure by Letters Patent is:

1. An automatic feeding mechanism of the class described comprising a hopper for containing work pieces; a chute leading from said hopper; carrying means electromagnetically operated for engaging a work piece on said chute and carrying the same to a certain position on said machine; means for de-energizing said electro-magnet means upon the carrying of said work piece to said position; electrically operated means for engaging said work piece instantaneously with the de-energizing of said electro-magnet means, automatically operated means for moving said engaging means to carry said work piece to operative position on said machine; and a rotatable drum for controlling the automatic operation of all of said means.

2. A feeding mechanism of the class described comprising: a hopper for containing work pieces; a chute leading from said hopper; electromagnetic members for engaging said workpiece and removing the same from said chute; a grinder; means for moving said electromagnetic members from said chute to adjacent said grinder; means for de-energizing said electromagnetic members at a predetermined position in the movement of the same toward said grinder, gripping means for gripping the workpiece simultaneously upon de-energizing said electromagnetic members; means for moving said gripping means to carry said workpiece into engagement with said grinder; means for automatically moving said gripping means away from said grinder after a predetermined time; and means for releasing said workpiece from said gripping members after said movement.

3. A feeding mechanism of the class described comprising: a hopper for containing workpieces; a chute leading from said hopper; electromagnetic members for engaging said workpiece and removing the same from said chute; a grinder; means for moving said

electromagnetic members from said chute to adjacent said grinder; means for de-energizing said electromagnetic members at a predetermined position in the movement of the same toward said grinder; gripping means for gripping the workpiece simultaneously upon de-energizing said electromagnetic members; means for moving said gripping means to carry said workpiece into engagement with said grinder; means for automatically moving said gripping means away from said grinder after a predetermined time; means for releasing said workpiece from said gripping members after said movement, and means for automatically energizing said electromagnetic members upon approach of the same to said hopper.

4. A feeding mechanism of the class described comprising: a shaft; a hopper; a chute leading from said hopper; means for rotating said shaft; a pair of gear wheels in spaced relation carried by said shaft and rotatable therewith; an auxiliary shaft; gear wheels mounted on said auxiliary shaft in spaced relation; chains for connecting corresponding wheels on said shafts; a plurality of electromagnetic members carried by said chains, the travel of said chains effecting the travel of said electromagnetic members into proximity with the chute; means for energizing said electromagnetic members upon approach of the same to the end of said shaft, said electromagnetic members engaging the workpiece at the end of said chute and conveying the same therefrom; gripping means for engaging the workpiece when conveyed away from said chute; means for de-energizing said electromagnetic members upon engagement of the workpiece by said gripping means; a grinding member; and means for moving said gripping means relatively to said grinding member subsequent to engagement of said workpiece with said gripping means.

45. In testimony whereof, I have signed the foregoing.

HUGH A. MCGILL.
